(57) CLAIM

The ornamental design for a gentle hair clip, as shown and described.

DESCRIPTION

FIG. 1 is a bottom isometric view of the gentle hair clip according to an embodiment of the new design;

FIG. 2 is a top isometric view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a bottom plan view thereof;

FIG. 8 is a top plan view thereof; and,

FIG. 9 is a front isometric view of the clip in an open position.

The broken lines are for environmental purposes only and form no part of the claimed design.
